COMBINED CLOCK AND PERPETUAL CALENDAR BOARD

Robert I. Genin, Scarsdale, N.Y., assignor to Child Guidance Toys Inc., New York, N.Y., a corporation of New York

Filed Apr. 13, 1965, Ser. No. 84,765

Term of patent 14 years

(Cl. D74—5)

FIG. 1 is a front perspective view of a combined clock and perpetual calendar board embodying my new design;

FIG. 2 is a front elevational view thereof, the time and calendar indicators being set in different positions from those of FIG. 1; and

FIG. 3 is a cross-sectional view taken on line 3—3 of FIG. 2.

The dominant features of my design reside in those features shown in full lines in the figures.

I claim:

The ornamental design for a combined clock and perpetual calendar board, substantially as shown and described.
